Primary Examiner — Darcey E Gottschalk*Assistant Examiner* — Bailey M Knotts(74) Attorney, Agent, or Firm — LEGALFORCE RAPC
WORLDWIDE(57) CLAIM

The ornamental design for a Santa LED lantern, as shown and described.

DESCRIPTION

FIG. 1 is a front top right side perspective view for a Santa LED lantern, showing our new design;

FIG. 2 is a front elevational view of FIG. 1 thereof;

FIG. 3 is a rear elevational view of FIG. 1 thereof;

FIG. 4 is a left side elevational view of FIG. 1 thereof;

FIG. 5 is a right side elevational view of FIG. 1 thereof;

FIG. 6 is a top plan view of FIG. 1 thereof; and,

FIG. 7 is a bottom plan view of FIG. 1 thereof.

The broken lines indicate unclaimed portions of the Santa LED lantern and form no part of the claimed design.

1 Claim, 7 Drawing Sheets
